UNITED STATES PATENT OFFICE.

JESSE L. D. KEPPI, OF BERKELEY, CALIFORNIA.

DESIGN FOR A HEATER.

Application filed August 27, 1928. Serial No. 27,965. Term of patent 14 years.

To all whom it may concern:

Be it known that I, JESSE L. D. KEPPI, a citizen of the United States, residing at Berkeley, county of Alameda, and State of California, have invented a new, original, and ornamental Design for Heaters, of which the following is a specification, reference being had to the accompanying drawing, forming part thereof.

The figure is a perspective view of a heater showing my new design:

I claim:

The ornamental design for a heater, as shown.

JESSE L. D. KEPPI.
